UNITED STATES PATENT OFFICE

BURNHAM C. STICKNEY, OF HILLSIDE, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed December 3, 1927. Serial No. 237,368.

This invention relates to the type-actions of type-writing machines.

An object of the invention is to produce a simple, compact and efficient system of radially-arranged front-strike type-actions which shall produce satisfactory impressions upon the work-sheet with a minimum of noise. It is also an object to organize the type-actions so as to make it practicable to build them into a standard typewriting machine in place of the ordinary noisy type-bars. It is an object to render the key-touch agreeable, and, further, to provide suitable means for vibrating the ribbon, and operating the ribbon-feeding mechanisms and the carriage-escapement mechanism.

Preferably there is employed an arcuate system of folding type-linkages, working in planes that radiate downwardly and outwardly from the printing point, each linkage having upper and lower case characters; the types preferably lying face downward at the rear ends of the type-linkages, and rising as they unfold, and then moving rearwardly to deliver the type-impressions. The unfolding movement of the type-linkage is effected at relatively high speed; and for the remainder of the printing stroke, the speed of the type substantially decelerates, said remainder being a backward float of the type-carrier on the links, to reach the platen. The type-linkage includes a rear drive-link and a forward guide-link, both fitted upon the framework of the typewriter, and a type-carrier which is floated upon the tips of said links and is normally in folded cumbent position.

A feature of the invention is the means whereby the inertia of the type-carrier is easily overcome by giving the key a maximum initial leverage upon the type-linkage, and gradually decreasing the key-leverage substantially throughout the unfolding movement of the type-linkage, and thereafter maintaining the key-leverage nearly constant throughout the remainder of the printing stroke. At the concluding portion of the printing stroke, while the type is within say a hundredth of an inch of the platen, it is moving at greatly decelerated speed, and prints

very quietly, due to such reduction in speed. When close to the platen, the type itself moves at about one-half or one-third of the speed of the free ends of said links, and said links at that time move at a speed which is less than the maximum unfolding speed of the type itself. The momentum of the operator's hand, when arrested at the bottom of the key-stroke, is utilized in pressing the type against the platen, or the paper thereon, the leverage of the key upon the type being relatively great (as compared with standard type-striking machines) at the moment of printing. The momentum of the entire type-action is also of assistance in compressing the type against the paper, to produce a clear impression and to conduce to satisfactory manifolding power.

In operating the type-system from a narrower key-lever-system, one of the problems consists in the provision of proper connection from the side keys to the side type-actions. Another problem is to secure the desired depth of key-stroke and the desired ease of touch, and yet avoid a high-speed, noisy type-impression. To this and other ends, the keys are mounted upon parallel levers which are in the form of rearwardly-extending bell-cranks which turn upwardly at their rear ends and are pivoted at their tops. The upwardly-extending arms swing back against upstanding sub-levers to operate the latter. Said sub-levers are pivoted at their lower ends upon the framework, and at their upper ends are connected forwardly to the type-linkages. The vertical arms of the key-levers are arranged to roll down upon the sub-levers.

This invention includes improvements upon the machine disclosed in my Patent No. 1,717,527, dated June 18, 1929.

Other features and advantages will hereinafter appear.

In the accompanying drawings, Figure 1 is a longitudinal sectional elevation taken about centrally of an Underwood standard front-strike typewriting machine embodying one form of the present improvements. This view shows the type-actions and

also the separate universal bars, one for operating the carriage-feed, and one for operating the ribbon vibrating and feeding mechanism.

5 Figure 2 is a front sectional elevation of the principal parts seen at Figure 1.

Figure 3 is a sectional detailed plan of the radially slotted segment, in which are detachably secured the individual brackets which 10 carry and guide the type-linkages seen at Figure 8, this being the preferred manner of mounting the linkages.

Figure 4 is an elevation showing the printing position of one of the key-actions seen at 15 Figure 1.

Figure 5 is a front sectional elevation corresponding generally with Figure 2, but showing the preferred form of type-actions and mountings which are seen at Figures 3 20 and 7-10.

Figure 6 is a sectional elevation of portions of the framework with the type-bracket segment seen at Figure 5.

Figure 7 shows in printing position a portion 25 of a type-action in perspective, and may be read in connection with Figure 8.

Figure 8 is a sectional side elevation showing in full lines the preferred form of type-action in printing position, and showing in 30 dotted lines the same in normal position. In this form, the type-actions are mounted individually upon brackets which are set into radial slots in a segment, a portion of which is seen at Figure 3, and another view at Figure 9.

Figure 9 is a sectional front elevation of a slotted segment having brackets or hangers in the slots and type-linkages pivoted upon the brackets.

40 Figure 10 is a perspective sectional view of the guide-link portion of one of the type-linkages, and the bracket upon which it is mounted.

Figure 11 is a sectional side elevation corresponding with Figure 1, and showing ribbon vibrating and feeding mechanism in normal positions.

Figure 12 corresponds with Figure 11, but shows the parts in printing positions.

50 Figure 13 is a detail of the ribbon-winding mechanism, and is to be read in connection with Figure 11.

Figure 14 is a diagram showing parts similar to Figure 8, normal positions being shown by full lines, and the dotted lines showing the positions about midway of the type-unfolding movement, and also the positions at the region where the upward type-unfolding 60 movement changes fully to a rearward floating movement.

Keys 10 surmount stems 11 of V-shaped levers 12, extending rearwardly from the keyboard and at their rear portions terminating in upwardly-extending arms 13, which are

pivoted at their upper ends upon a transverse, horizontal fulcrum-rod 14 arranged at about the level of the keyboard, so that the keys may swing downwardly and a little rearwardly. The key-levers work in vertical slots 15 in a transverse bar 16 forming part of the framework, and swing in parallel planes.

Said key-lever-arms 13 have vertical treads 17, which roll upon curved treads 18 that are provided upon a system of vertical sub-levers 19 preferably of the third order, their upper ends being connected by pull-links 20 to type-linkages, and their lower ends being pivoted upon a transverse fulcrum-rod 21. Each type-linkage includes a rear cumbent drive-link 22, a forward upstanding guide-link 23, and a folded cumbent type-carrier or float 24, having upon its tip a double type 25.

The system of type-linkages is narrower 85 than the system of key-levers 12. The width of the system of sub-levers 19 at the top is about equal to the width of the system of type-linkages. Towards their lower ends, said sub-levers fan out from side to side of 90 the machine to about the width of the key-lever-system; and their fulcrum-rod 21 is bowed downwardly, and at their lower ends said sub-levers 19 work in radial slots 26 formed in a fulcrum-bar 27. Said sub-levers 95 19 are all straight, and, viewed from the front, radiate upwardly and inwardly from the broadly curved fulcrum-bar 27. Said sub-levers 19 extend upwardly behind and above the horizontal transverse row of key-lever-arms 13; and at 28 the tops of the sub-levers are pivoted to the rear ends of the pull-links 20 at points above the key-levers. Some of the sub-levers at their upper portions curve 100 forwardly over the key-lever-tips, as at 29.

The upright arm-portions 13 of the key-levers form treads or rocker-portions to roll down along the treads 18 of the sub-levers 19; and these portions 13 are bent more or less inwardly to form diagonals, producing a converging arrangement, as seen from the front, Figure 2, to agree with the arrangement of the sub-levers 19. To guide the levers and also to keep the rocking edge of each in registry with its associated sub-lever, there are 110 provided for the key-levers, in addition to the vertical slotted guides 15, a vertical guide-comb 30 for the elbow-portions of the key-levers (so that the arms 13 are guided at top and bottom) and a vertical guide-comb 31 for the key-levers just in rear of the keyboard. No trouble arises from lateral binding or twisting of the key-levers, even though the system of key-levers has less width at the fulcrums 14 than at the elbows 32.

At their upper ends, the sub-levers 19 are 120 provided with tips 34 to work in a curved guide-comb 35, which is cooperative with the lower radial slots 26 to guide the sub-levers. The sub-levers are of graduated lengths and 130

form a system which is curved at its upper end to conform generally with the curvature of the system of type-linkages; while the system of key-levers extends horizontally across the machine.

- 5 The pull-links 20 include turnbuckle-portions 33, to make them extensible, for securing proper contact and coaction of the rolling edges of the levers with each other.
- 10 The type-linkages are normally in folded condition, with the type-carriers or floats 24 lying cumbent with their type-carrying tips extending rearwardly. Each float is of elbow-construction, one arm extending from the 15 rear drive-link 22 to the type 25, and the other arm extending from the drive-link 22 upwardly and forwardly to the forward guide-link 23.

The pivoting of each of the rear drive-links 22 to the type-carrier or float is indicated at 20 36. The pivoting of the forward guide-link 23 to the same type-carrier is indicated at 37.

The drive-links 22 in one form of the invention are pivoted upon a rear fulcrum-rod 25 38 which is curved concentrically with the printing point at 43, said rod being fixed in a segment 39 which has radial guide-slots 40 for the hub-portions of the drive-links; the forward ends of the pull-links 20 extending 30 forwardly over said segment 39. For the drive-links 22, a slotted guide or comb 41 may be fastened by screws 42 to the framework, and extend rearwardly and upwardly over the segment 39 to a point in the rear thereof, 35 guiding said drive-links throughout their printing strokes. This guide-comb 41 may curve concentrically to the printing point 43. The type-carriers 24 may be partly guided by means of projections 45 formed upon their 40 forward hub-portions where they are pivoted to the guide-links 23; said projections 45 working in slotted portions 45^a of a guide-comb 46 fixed in the machine above the guide-links 23, and also curved concentrically with 45 the printing point 43. By means of the combs 41 and 46, the links and the type-floats or carriers are constantly guided, so that they may move freely and accurately to the point where the types enter the common center guide at 50 the front of the platen. The types at the side of the system may be also supported in part by the drive-link 22 at points thereof near the fixed guide-comb 41.

A curved or segmental dust-shed 47 may be 55 secured to the front of the slotted segment 39 by screws 48, and extend rearwardly over the segment 39, to keep the slots free from particles that fall from the work-sheet. The drive-link 22 near its hub-portion may have 60 a goose-neck portion 49 formed to clear the dust-guard 47 in front thereof.

The pivotal attachment 50 of the pull-link 20 to the drive-link 22 is above the dust-guard 47.

65 When the drive-link 22 is pulled rearward-

ly by the link 20 and the sub-lever 19 at the 70 operation of the key 10, the drive-link 22 swings upwardly to about a vertical position, thus unfolding the type-linkage until the type reaches a point forwardly of the platen. From this point the type-carrier is floated backwardly upon the links 22, 23 to the platen, by which it is arrested.

The key-levers may be individually returned to normal positions by means of a 75 transverse horizontal row of coiled diagonal springs 51, extending forwardly and downwardly from the upper ends of the lever-arms 13, and anchored at their lower ends upon a bracket 52 fixed upon the framework. The type-linkages may be individually returned by means of radial diagonal tension 80 springs 53, attached at their upper ends to the drive-links 22, and at their lower ends to a bracket 54 also secured to the framework. The leverage of each spring 53 decreases during the printing stroke. Each of the drive-links may be provided with a guiding ear 55, to maintain engagement with the 85 guide-comb 41 at the last portion of the 90 printing stroke.

As seen from the front at Figure 2, the type-linkages converge directly to the printing point 43, and the segment 39 and the slotted guide-link-segment 56 are curved concentrically with said printing point; while the sub-levers are less convergent than the type-bars, but at their upper ends stand about directly in rear of and level with the points 50 where the pull-links 20 engage the drive-links 22, so as to conduce to efficiency and avoid appreciable side strain or binding. The width of the system of sub-levers at their upper ends is about equal to the width of the system of drive-links 22 at the points 50 95 where they are pivoted to the pull-links. Each key-lever tread 17 may be extended downwardly, if desired, at 57, to carry the rolling contact down as far as desired in each instance towards the pivot 21 of the sub-lever. The springs 51 hold the key-levers up against a cushion or rest 58, while the springs 53 pull the types down against a curved cushion or rest 59. The turnbuckles 33 are 100 individually adjusted to secure the desired contact of the arms 13 and 19 at the beginning of the key-stroke, and to compensate for unevenness in the normal positions of types 25 or levers 12. The sub-levers fan out toward their lower ends in an arc upon a common fulcrum-wire, said lower ends being 105 lower than the key-levers. The upward arms of the key-levers are also made divergent to coincide with their respective sub-levers. The key-levers are guided at their pivots 110 and also at their elbows, and also at their key-ends to avoid side strain or binding at the sides of the system. All of the sub-levers move freely in their converging planes and are free from binding or side strains.

The speed of the upward unfolding of the type-linkage is rapid in proportion to its subsequent rearwardly floating speed towards the platen; and this disproportion is increased by retarding the type end of the carrier 24 as it nearly touches the platen. This final retarding is partly effected by the aid of link 23, which reaches at its upper end to a point above the level of the pivot 36 as the type approaches the platen, Figure 1. At this time, as both links about complete their rearward swing, the guide-link 23 is on the down-swing, and carries the forward end of the type-carrier downwardly, whereby the type-carrier tends to turn towards the left at Figure 1, around the point 36; or, in other words, the type 25 itself is retarded or decelerated, so that the speed of the type, as it is almost in contact with the platen, may equal only about one-half or less of the speed of the link-pivots 36, 37. The speed of the type is brought down so that it is arrested without objectionable noise. However, the shock of the slowly moving type against the platen or paper is heavy, because the platen must serve to arrest the finger and the hand of the operator, which is still driving down upon the depressed key 10. The type and platen must arrest the various parts of the type-action as well, including the key-lever, the links, and the type-carrier itself. At the same time the key has enough leverage to enable the pressure of the operator's hand to aid in pressing the type against the platen. From all of these causes, a satisfactory impression may be secured, without giving the type the quick blow which is so noisy in common typewriters.

This arrangement of the linkage gives the type-carrier such a path as to secure clearance between the same and the platen-paper-feeding devices and other adjacent devices in the typewriting machine, and also gives a desirable relation between the upwardly-unfolding portion and the rearwardly-floating portion of the printing stroke of the type-carrier.

In order to make the operation of the key easy and to avoid the shock to the finger, the key is given a great leverage upon the type-linkage at the beginning of the printing stroke. For this purpose, the point of contact between the key-lever arm 13 and the sub-lever 19 is normally relatively close to the key-lever pivot 14. Ease of key-touch may be preserved beyond the initial portion of the key-depression, by arranging for the contact between said levers 13 and 19 to remain quite near the pivot 14 of the key-lever throughout a substantial portion of the key-depression. As the type gathers headway, however, the point of contact between said levers 13 and 19 is gradually shifted down farther from the key-lever pivot 14, and nearer to the pivot 21 of the sub-lever, thereby

continually decreasing the leverage of the key upon the type-linkage, without making the key-touch harsh, and tending to store up in the type-linkage some energy imparted by the hand of the operator. This decrease of leverage may continue until the type-linkage is substantially unfolded, and the type-carrier begins its relatively-slow rearward printing movement. From this time on, it is not necessary to decrease rapidly the leverage of the key upon the type-linkage, but rather it is a desideratum to maintain the leverage near the point where the movement of the type-carrier changes from its upward unfolding movement to its rearward printing movement. It is desirable, at the actual contact of the type with the paper, that the leverage of the key upon the type shall remain fairly good, so that pressure on the key may aid in producing substantial pressure of the type against the platen at the instant of arrest. Moreover, it is desired to avoid speeding up of the type at the conclusion of the printing stroke of the key. For these reasons, the leverage of the key upon the type-action does not need to be decreased substantially during the rearward floating of the unfolded type-carrier, that is, during the time when the type is within say one-half an inch of the platen. The weight of the moving type-linkage may, however, be so great that it will effectually resist the tendency of the hand to speed up the linkage near the conclusion of the printing stroke, even if the key-leverage upon the drive-link is diminished at this time beyond the point illustrated.

The type-carrier is so mounted upon its links that in printing position the guide-link may form an obtuse angle with the type-carrier, that is, with a line drawn from the type to the joint of the type-carrier with the guide-link, and liability of spring of the guide-link rearwardly past its true position when the type is arrested by the platen, may be avoided. Hence the type delivers a solid, clear-cut impression.

The resistance of the key to the touch may be kept at a low point throughout the printing stroke, giving the effect of an easy key-touch and also avoiding excessive momentum, or excessive speed of the type-action, and unnecessarily heavy type-impressions and unnecessary noise of impact. At first there is but little rolling of one lever along the other, so that the leverage of the key remains great until the type-carrier 24 has moved up a substantial distance. Then the key-lever arm 13 rolls upon the sub-lever tread 18, thereby gradually decreasing the key-leverage, until nearly the completion of the unfolding or high-speed portion of the travel of the type 25, whereby undue resistance of the key to the finger-pressure is avoided and the touch is kept easy, and the type-linkage is not unduly speeded and does not acquire undue

130

momentum. During the remainder of the key-stroke, there may be little or no further roll or downward creep of the contact-point towards the sub-lever fulcrum 21. So after 5 the change from the high-speed, unfolding motion of the type to the low-speed, rearwardly-floating motion of the type, the leverage of the key upon the type may be kept constant, or nearly so, thereby conduced to 10 relatively-low speed of the type, so that the speed will not be excessive at the moment of impact, and so that the leverage of the key upon the type shall be as high as practicable to 15 secure sufficient pressure of the type upon the platen or paper.

A substantial advantage is gained by the provision of one lever rolling upon another lever, since, by this means, the leverage can be readily shifted, as and when required; the 20 leverage of the key upon the type being say fifteen to eighteen times as great at the beginning of the key-stroke as at the end thereof. This extraordinary leverage at the beginning of the stroke overcomes the normal 25 resistance of the type carrier 24, the first part of whose unfolding motion is extremely abrupt, owing to the manner in which it is mounted upon the links 22 and 23; and, in addition, the carrier necessarily has considerable 30 size and weight and is therefore heavy.

It will be seen that the downward and upward movement of the key effects a rearward movement and a forward movement of the sub-lever; the arm 13 and the sub-lever arm 35 19 standing edge to edge in rear of the type-linkage-system, or, in other words, the type-linkage-system being mounted between the keys and the vertically-standing roll-lever arms. This gives compactness and affords 40 simplicity of construction and operation, and accessibility, and produces a mechanism which can be manufactured at low cost and inserted in standard typewriting machines in lieu of the usual key-actions, as, for example, an Underwood standard machine.

It will also be seen that the rolling lever-arms occupy the lower part of the machine-frame, the upper part being occupied by type-linkage, and that the pull-links 20 extend 45 forwardly from the sub-levers and beneath the type-basket 59 to the drive-links 22, whose segment is forward of the type-basket, and that the type-carriers 24 normally lie between the type-basket and the 55 segment 56, which carries the system of guide-links 23.

The use of a key-lever having a rear elbow pivoted at its upper end and a sub-lever of the third order, pivoted below said elbow 60 and extending up in rear of said key-lever arm 13 and connected at its upper end to the type-linkage, presents the advantage of efficiency and of compactness and simplicity in manufacture, and affords the further advantage 65 that the sub-lever-system can be

fanned out and thus be made at its upper end as narrow as the type-linkage-system, and at its lower end as wide as the key-linkage-system. There may be a diagonal line of 70 rolling of the key-lever arm 13 upon the sub-levers 19 to accommodate said fanning out of the sub-levers, the diagonal line being slight and the key-levers, nevertheless, working in vertical planes without liability of binding from the diagonal position of the key-lever arms 13, as viewed from the front of the machine. 75

It is found in practice that the contact of the type with the platen may be accompanied by more noise than is accounted for by the speed of the type itself or by the hardness of the platen. As the type-carrier 24 approaches the platen, it tends, by reason of centrifugal force, to fly upwardly bodily from the links 22 and 23. When the type is arrested by the platen, the drive-link 22 tends to continue its backward swing and to carry back the lower end of the type-carrier, which therefore momentarily tends to swing downwardly and forwardly about pivot 36. This tendency is arrested by the guide-link 23, which receives a downward pressure from the forward end of the type-carrier; this downward pressure being caused, as just explained, by the arrest of the type and by the 90 constant tendency of the type-carrier to turn backwardly around the pivot 36 and downwardly at the pivot 37. This sudden change at the pivot 37, from an upward pull of the type-carrier (immediately prior to printing) 100 to a downward thrust (due to the arrest of the type), causes a knock in the link-joints 37 and 65. This knock is overcome by means of a tension spring 60, which, at its upper end, may be attached to the type-bar as shown, or it may be caught through an axial hole indicated by a dotted circle 61 in the pivot 37, and, at its lower end, may be caught upon a curved bracket 62 fixed upon the slotted segment 56 in which the guide-links 23 vibrate. The springs keep the joints 37 and 65 105 constantly closed, avoiding noise. These springs occupy positions between the guide-links 23 and the arms 63 of the type-carrier. 110

This tendency to knock in some forms of the invention may be further reduced by bulging the type-carrier rearwardly at 64, so that, when the type is approaching the printing line, the weight of the bulge-portion 64 will be on the opposite side of the pivot 115 36 from the bulk of the weight of the type-carrier, so that there is a tendency of the portion 64 to turn the type-carrier in a direction to hold the link 23 constantly down upon its pivot-rod 65. That is, the tendency of the bulge 64 is to counterbalance the weight of the main portion of the type-carrier at this time, for the purpose stated.

At Figures 3 and 7-14 is shown the preferred form of type-linkage and the mount- 120 125 130

ing and guiding thereof, this form being operable by the same key-lever and sub-lever action that has been described.

In this preferred form, the drive-link 66 is used the same as 22, for unfolding the type-linkage and floating the type-carrier to the platen; and it is mounted upon an individual pivot 67 corresponding with 38. A short front guide-link 68 is shown corresponding with 23 and pivoted at 69 at a point substantially higher than pivot 67. The triangular type-carrier 70 is pivoted at 71 and 72 to the free ends of said links 66, 68.

The guide-link 68 is much shorter than 23, making a short reach from the pivot 69 to the platen and conducing to stability of the type-bar and efficiency in delivering type-impressions. The elbow-shaped type-carrier 70 forms a triangle whose sides are about equal in length. Owing to this form, it may be of minimum size and maximum efficiency, while, owing to its mounting, its type-end is given such a path 73 as to clear the usual paper-guiding devices 74, etc.; while normally the type-carriers compactly occupy a position in rear of the links 68 and with the types directly overlying the pivots 67. The drive-link 66, whose length is about equal to that of the rear side of the triangular type-carrier 70, may swing through substantially less than ninety degrees; while in normal position it extends towards the pivot 69 and about in line therewith, preferably a little below a line joining 69 to 70. With the proportioning and mounting aforesaid, and with the pivot 72 spaced considerably back of the pivot 69, the type-linkage is easily started into action, and its entire movement is rendered smooth, and the touch upon the keys is better controlled by the rolling of the sub-levers 19, and the imparting of excessive momentum to the type-linkage is avoided, tending to quietness of type striking. There is avoided excessive travel of the type at any stage, in proportion to the travel of the drive-link 66.

In this construction, the speed of the type is substantially retarded near the platen, and especially when it is as close as one-sixteenth or one-thirty-second of an inch to the platen. There is shown diagrammatically in straight dotted lines at Figure 8 a position of the linkage, from which it will be seen that pivot 71 will, at the last part of its printing stroke, travel a much greater distance than is traveled by the type 25; or in other words the speed of the type is relatively or proportionately greatly decelerated, with resultant minimizing of the noise of impact. This special deceleration is mainly effected by causing link 68 at this stage to have a much inclined position. Its free end or pivot 72 is moving downwardly as well as rearwardly; and the obliquity of movement is so great as to cause the carrier 70 to turn relatively towards the

left at Figure 8, about pivot 71, as the latter travels rearwardly in about a horizontal direction. Thus, as the type-carrier 70 is floated rearwardly upon its pivots 72 and 71, its type is given an independent movement of retardation about the pivot 71, thus resulting in substantial deceleration with the result above noted.

Preferably, each type-linkage is mounted upon an individual hanger, designated generally as 75, and inclusive of a supporting plate or hanger 76 and forward and rear arms 77, 78 branching therefrom. The hangers are radial, and each arm 77 carries pivot 69, while each arm 78 carries a pivot 67. The plates 76 are fixed in slots 79 formed in a segment 80 curving downwardly and forwardly, said slots 79 radiating downwardly and forwardly from the printing point 43, and being so placed that the arms 77 and 78 are about equal in length. The hangers are held in the slots by means of bolts 81 having heads 82, Figures 3 and 8. Each head may overhang both adjoining hangers. Said heads overlie a segmental fastening plate 83. The bolts extend through holes 84 formed in the segment, and are drawn tight by means of nuts 85. The bolts clamp the segment-plate 83 upon the edges of the hangers 76 which protrude from the segment. Each hanger has a shouldered portion 86 on one side, Figure 3, which fits over the finished forward face 87 of the segment. When inserting or withdrawing a hanger, the adjacent nuts 85 may be loosened to permit the hanger to be lifted out of its slot 79. The bolts have flattened sides 88 to clear the hanger-plates 76, and permit their endwise insertion and withdrawal while the loosened bolt remains in place. It will be perceived that after the adjoining hangers are withdrawn, any bolt may be released by removing its nut, and the bolt withdrawn. In inserting the hanger, it is pushed down until a shoulder 89 formed on one face or side of the hanger-plate abuts against the upper finished face of the segment 80, so that the type-linkage is mechanically located in proper position.

The springs 60 at Figure 8 may be pivoted at their lower ends to pins 90 provided upon the hanger-arms 78 below the pivot 69, in such position that the line of pull of each spring is constantly approximate to a line joining the pivots 69, 72, so as always to hold said pivots tight, while not unduly affecting the movement of the linkage.

One of the advantages of the hanger 77, 78 is that it permits compactness of the links 68 for which the room is restricted, and which must be confined closely side by side, as will be understood from Figure 5. For compactness and stiffness, this link is folded lengthwise at 91; and it may be given a U-shape to afford clearance for the spring 60. At its upper end the link is formed with opposite

ears or forks 92, Figure 10, which bestride a pivot 93 of large diameter, having oppositely projecting central stud-portions 94, extending through the opposite ears 92, the studs being riveted or headed over onto the ears 92, thus strengthening the link at this region and also forming a thin but ample bearing for the type-carrier 70, whose hub 95 is freely confined between the ears 92. In this manner the requisite thinness of bearing is secured, and the links 68 can work in the confined space which they must occupy.

Upward from the hub-portion of the type-carrier projects a guiding nib 96, corresponding with 45, and milled to a thin condition, and working in one of the radial guide-slots 97 corresponding with 46 and formed in the under side of a fixed segment 98. Although the restriction of space makes it necessary for the guiding nibs 96 to be very thin, still this arrangement affords the desired guiding of the type-linkage at this point, which is within a short distance from the printing point 43, whereby the type is efficiently guided towards the central fixed type-guide 99, and the linkage is also efficiently supported against buckling and shivering at the impact of the type.

Upon the rear branch 77 of the type-bar hanger may be provided a horn 100 by which may be lightly guided the drive-link 66; preferably said link is provided with an ear 101 bent to one side at Figure 7 and having a slot 102 which embraces said guiding horn 100. Dust and falling particles may be kept off from the pivots 67 by a dust-shed 103 in the form of a segment covering all of said pivots and suitably supported at its ends; the drive-link 66 formed with clearance 49 for said dust-guard 103.

At Figure 14 is shown in full lines the normal position of the type-linkage with the upright key-lever arm contacting (at 103^a) near its fulcrum with the upper portion of the roll 18 of the sub-lever. This gives the key maximum leverage upon the type-linkage, for starting the same easily. This leverage is substantially maintained throughout about the first half of the unfolding movement of the type-linkage, at which stage (103^b) the key may be half way down. At this point there begins a very great decline in the rate of travel of the type compared with the rate of the drive-link 66, as the upward unfolding movement merges into the rearward floating movement. At said point 103^b there also begins a rapid rolling of the lever-arm 13 upon the sub-lever 19, until (at 103^c) the key has nearly its minimum leverage upon the type as the latter begins to float rearwardly upon the links. From this point on, the change of leverage of the key upon the type-carrier is relatively small, the point of application of power of the key-lever to the sub-lever now remaining near the maxi-

mum distance from the key-lever pivot and near the minimum distance from the sub-lever pivot. Owing to the reduction in key-leverage, the type-action tends to absorb the momentum of the hand of the operator, and the key tends to slow down. The drive-link 66 may be weighted on its free end portion at 104, and the type-carrier itself may also be weighted near its hub-portion 105, these parts now moving at relatively high speed and increasing the shock of the type against the platen. Thus, though the speed of the type is at minimum at the impact, still it must assume the burden of arresting the heavy type-linkage and the hand of the operator, so that a good impression is secured with a minimum of noise.

At its lower end each guide-link 68 has ears 106 embracing the thinned upper end 107 of the hanger-arm 78. At this end, the link 85 68 has a pivot similar to 92, 94 already described, and designated as 108, 109, the opposite stud-portions 109 being riveted over the ears 106 to stiffen the link and confine it upon the arm 78, the latter having a pivot-hole 110 to fit upon the pivot 108. 90

The platen is mounted upon the usual Underwood platen-shift-frame 111, which shifts up and down upon a carriage 112 mounted upon a guide-rail 113. Upon the framework of the machine is usually mounted a shift-frame 114^a including a shift-rail 114 for supporting the platen-frame 111. The carriage has a rack 115 meshing with a pinion 116, connected to an escapement-wheel 117 controlled by a pair of bevel feed-dogs 118, 119, having a returning spring 120 and a stop 121. To operate this Underwood carriage-feeding mechanism, there may be provided upon the sub-levers 19 rearwardly directed tappets 122 to swing down about the pivots 21 against a universal bar 123, which is in the form of a bail having opposite arms 124 that are rigidly connected by a rock-shaft 125. From this rock-shaft extends rearwardly an arm 126, connected by an extensible thrust-link 127 to an arm 128 provided upon the dog-rocker 129, this link being longitudinally slotted at its upper end at 130 to fit detachably upon an operating pin 131 provided upon an arm 132 of the dog-rocker, said arm being slotted to receive the upper end 133 of the link 127. The upper portion of the link has a threaded bottom shank 134 screwed down into the top of the main link 127, to permit endwise lengthening of the link and thereby effect corrective adjustment between the universal bar 123 and the arm 129. A returning spring 135 may also be provided for the universal bar, the spring also aiding in starting the type-bars back from their printing positions. Spring 120 also affords similar aid, and further aid may be derived from the usual camming action of the escapement-wheel 117 upon the usual beveled dogs 125

118, 119 of the Underwood typewriting machine. The tappets 122 are at different heights and of different lengths, to impart substantially uniform movements to the universal bar; and any tappet may be filed or bent for correction of its action.

To vibrate the ink-ribbon 136, mounted upon the usual Underwood spools 137 at the sides of the machine, the ribbon is threaded 10 through a vibrator or ribbon-shield contrivance 138 back of the type-guide 99. The type-guide is mounted upon a front horizontal cross-bar 139 which extends beneath the type-guide forks or prongs 99 and is riveted 15 at 140 to the front of said prongs; said cross-bar 139 at its ends being bent down to form diverging supports 141, which extend to the opposite sides of the machine, each being there secured by screws 142 to the main framework 143. The prongs 138 of the ribbon-vibrator device extend up from a U-shaped operator 144. Said operator has a shank 145, the bottom whereof is pivoted at 146 to the forward end of an arm 147, which 20 is pivoted at 148 upon a bracket 149, that is screwed upon the platen-shift-rail or frame 114 to shift up and down with the platen. The arm 147, together with the ribbon-vibrator 144, is operated by means of a universal bar 150 that extends transversely of the machine beneath the key-lever elbows and is 25 operated uniformly by lugs 151 depending from the various key-levers. The lugs are of sufficient length to afford slight corrective 30 bending, to secure uniformity in the operation of the universal bar 150. The stroke of the latter continues throughout the key-stroke, so that the vibration of the ribbon is effected at a relatively slow rate, thus minimizing 35 liability of the ribbon to overthrow, and also easing the key touch. It may be here noted that any tappet 122 may be cut off when it is desired to operate the ribbon without feeding the carriage, at the key-stroke, 40 thus making it unnecessary for the employment of special mechanism when it is desired to provide the machine with silent keys.

The universal bar 150 extends horizontally 45 across the machine, and has at its ends opposite arms 152 fixed upon a horizontal rock-shaft 153. Upon the rock-shaft is provided an arm 154, to which is connected a returning spring 155, and to which is also connected an upwardly and rearwardly extending pull-link 156. At its upper end provision is made 50 for connecting said link to an arm 157, which is fixed upon a transverse horizontal rock-shaft 158, the latter mounted in fixed brackets 158^a and 158^b, Figure 2, and having a pendent arm 159, connected by a link 160 to the ribbon-vibrating arm 147 already described. Said link 160 vibrates up and down idly at 55 the case-shifting operation. When a key is depressed, the universal bar 150 is swung rearwardly, and arm 154 is swung down-

wardly, together with link 156, which pulls down arm 157 and vibrates rock-shaft 158, thereby swinging forwardly the arm 159, and by means of link 160 the arm 147 is vibrated to lift the ribbon to cover the printing point. The arm 157 may be provided with an adjustable stop 161.

The aforesaid long pinion-vibrating arm 157 is provided with operating pin 162, engageable by a rear slot 163 in the upper end 75 of the main operating link 156. Upon the rock-shaft 158, to which the long arm 157 is secured by a set-screw 164, there is also secured a short arm 165, having its operating pin 166, engageable by a forward slot 167 80 that is also provided in the upper end of link 156. The link may therefore be articulated at will either to the pin 162 or to the pin 166, thus giving either a short stroke or a long stroke to the ribbon-vibrator 155, to bring 85 into use either one of the color stripes shown upon the ribbon. The bringing into use of either pin 162 or 166 is effected by swinging the upper end of the link towards or away from the reader at Figures 11 and 12, this 90 shifting operation being effected by means of the color-shift key-lever 168 mounted at the usual place in the front of the typewriting machine. Said lever is mounted upon a rearwardly extending rock-shaft 169, suitably supported in the framework at 170 and elsewhere, and at its rear end having a crank 171 constantly engaging a slot 172 in an ear 173 that is bent off from the link 156 at its upper end. As the shaft 169 is dropped by one of its color keys, the crank 171 is swung 100 towards or from the reader, and, by reason of its engagement with the slot 172, the upper end of the ribbon-operating link 156 is given a corresponding color-shift; said slot 172 105 extending longitudinally of said link, preferably parallel therewith, so that the link will ride freely upon said crank or pin 171 during the type-key strokes; said crank 171 being, however, parallel with the shaft 169 110 and the ear 173 being at an acute angle to said crank 171, since the ear extends in the direction of the pull of the link 156.

At its upper end the link 156 terminates in a guiding tongue 174, working in a horizontal cross-slot 175 in a guide-bracket 176 that is suitably supported upon the framework by means of screws 177. The slot 175 permits the side-to-side color-shifting of the link 156, while guiding it against accidental forward or backward displacement.

For stenciling purposes, the active link 156 may be maintained in a midway idle shift-position by adjusting the shaft 169 to its midway or stenciling position, so that the crank 171 occupies a midway position. The arms 157 and 165 with their pins are separated sufficiently to admit of the disengagement of the operating link 156 from both pins at the same time.

There may be provided upon the upper end of the link 156 a lug 178, which, at the up-stroke of the link, engages the arm 157 to vibrate downwardly the ribbon-vibrator 136, so as to insure that the ribbon shall stand below the line of typing when stenciling.

It is desired that the ribbon-spools 137 shall occupy their usual positions upon the machine, and it is also desired to increase the length of that portion of the ribbon which 5 extends close to the platen at each side of the printing point, so as to give clearance to the type-actions at the sides of the system, where the types rise near the front of the platen, as will be understood from the type-path shown at 73, Figure 8. Accordingly, the ribbon is carried straight along the platen from side to side of the type-linkage system at the upper border thereof, as will be understood from Figure 2. It is, however, desired 10 that the spools remain stationary as usual at the ribbon-vibrating operation, while at the printing point the ribbon must be vibrated up and down to the usual extent. There 15 arises a difficulty in managing the ribbon between the printing point and the spools, inasmuch as a great length of ribbon extends horizontally along the platen and close thereto from the opposite sides of the ribbon-vibrator 138. The length of ribbon extending 20 obliquely from each spool to the platen is very much shorter than heretofore, and one end of this short length it is desired to vibrate while the other end is stationary, without 25 creasing, fouling or snarling of the ribbon. To this end, there are provided subsidiary 30 corner-guides 179 at opposite sides of the printing point and spaced therefrom, being situated at the ends of the great length of ribbon 180 which is kept close to the platen; and the ribbon turns corners over these guides 179 and runs obliquely forward to the spools 137. These corner-guides are mounted upon arms 181, which swing up and down at the ribbon-vibrations, the extent of vibration of the 35 corner-guides 179 being considerably less than the vibration of the central main ribbon-guide 138. The central ribbon-vibrator 138 is preferably itself mounted upon the same arms 40 181 as the guides 179, so as to vibrate therewith. Hence, while the ribbon is vibrated 45 up and down to a sufficient extent at the printing point, its vibration is made considerably less at the corners 179 near the spools 50 137, so that the ribbon is successfully carried along the platen for quite a distance to points near the spools, without engendering a tendency to snarl or foul the ribbon or strip it 55 down or up from the spools by reason of the vibration of the ribbon at the printing strokes. This advantage is gained because 60 said vibration is relatively small at the corners where the ribbon leaves the vibrator, and the corner-guides 179 are relatively close 65 to the pivots 182 of vibrating arms 181, and

move up and down correspondingly less than does the central two-part ribbon-vibrator 138 at the printing point. The operating shank 144 at its upper end is provided with transverse slots 183, engaging operating pins 184 on the inner ends of said ribbon-vibrator levers 181, so as to vibrate the levers and ribbon up and down at the keystrokes. Said pins 184 are provided upon ears 185, which are bent forwardly and upwardly from the inner ends of the levers 181, and may also serve to guide the inner ends of said levers. There may be also provided midway ribbon-guiding pins 186 arranged on the levers 181 between the guides 179 and 138.

One of the arms 152 may be provided with a spring-pawl 187 to engage a ratchet-wheel 188 on transverse shaft 189, geared to upright spool-shafts 190 to wind the ribbon in the manner usual in the Underwood machine.

Variations may be resorted to within the scope of the invention, and portions of the improvements may be used without others.

Having thus described my invention, I claim:

1. In a front-strike typewriting machine, the combination with a platen, of a system of type-keys, a system of rearwardly-extending key-levers whereon the keys are mounted, said key-levers in the form of elbows which at their rear portions turn upwardly and are pivoted at their upper portions, a system of pivoted sub-levers which extend up and down and against which the upwardly-extending arms of the key-levers swing edgewise, and a system of type-linkages to which the sub-levers are connected by means of links extending forwardly from the sub-levers to the type-linkages, the vertical arms of the key-levers being arranged to roll upon the sub-levers, each type-linkage including a rear drive-link connected by an adjustable connection to its sub-lever, and also including a forward upstanding guide-link, and also including a type-carrier pivoted upon said links and normally in folded cumbent position.

2. In a front-strike typewriting machine, the combination with a platen, of a system of type-keys, a system of rearwardly-extending key-levers whereon the keys are mounted, said key-levers in the form of elbows which at their rear portions turn upwardly and are pivoted at their upper portions, a system of pivoted sub-levers which extend up and down and against which the upwardly-extending arms of the key-levers swing edgewise, a system of type-linkages to which the sub-levers are connected by means of links extending forwardly from the sub-levers to the type-linkages, said key-levers working in substantially vertical planes and pivoted at about the level of the keys, said rear key-lever-arms forming a horizontal transverse row and having up and down treads, and a

- curved fulcrum-rod whereon said sub-levers are pivoted at their lower ends, said sub-levers having means to guide their upper and lower ends and being of varied lengths to accommodate the arcuate arrangement of the system of type-linkages below the front of the platen, the system of type-linkages being narrower than the system of key-levers, the width of the system of sub-levers at the top being about equal to the width of the system of type-linkages, said system of sub-levers fanning out from side to side and at their lower ends about equal in width to the key-lever system and working in radial planes, said sub-levers extending upwardly in rear of and above the row of key-lever-arms and being pivotally connected to the type-linkages at points above the key-levers, said upright arms of the key-levers forming treads or rocker-portions to roll down upon the sub-levers, said rocker-portions bent radially to correspond with the spreading arrangement of the sub-levers, said key-levers guided laterally at their pivots, at their elbows, and at their key-ends.
3. In a front-strike typewriting machine, the combination with a platen, of a system of type-keys, a system of rearwardly-extending key-levers whereon the keys are mounted, said key-levers in the form of bell-cranks which at their rear portions turn upwardly and are pivoted at their upper portions, a system of pivoted sub-levers which extend up and down and against which the upwardly-extending arms of the key-levers swing edgewise, a system of type-linkages to which the sub-levers are connected by means of links extending forwardly from the sub-levers to the type-linkages, the vertical arms of the key-levers being arranged to roll upon the sub-levers, each type-linkage including a rear drive-link connected to its sub-lever, and also including a forward up-standing guide-link, and also including a type-carrier pivoted upon said links and normally in folded cumbent position, returning springs connected to said key-levers and extending forwardly and downwardly from the pivotal portions thereof, and returning springs connected to said type-linkages and radiating forwardly and downwardly from said drive-links from points near the fulcrum thereof, the leverage of the returning spring upon the drive-link substantially decreasing during the printing stroke.
5. Machine constructed according to claim 2, the sub-levers being substantially less convergent than the type-bars, and at their upper ends standing about directly in rear of and level with the points of engagement of the pull-links with the drive-links.
6. In combination, a system of rearwardly-striking type-linkages, a system of keys, a system of connections from the keys to the type-linkages affording a maximum leverage of the keys upon the type-linkages at the beginning of the key-strokes and decreasing leverage during the printing strokes, each type-linkage including a rear link, a front link pivoted upon the framework, and a carrier normally folded and pivoted upon the free ends of said links for an upward unfolding motion and a rearward floating motion to the platen, said type-carrier having a type at its upper end, the pivot of the forward link being at a point substantially higher than the pivot of the rear link and moving in a rearward and downward path at the conclusion of the printing stroke, thereby rotating reversely the type-carrier upon its point of pivoting to the rear link and consequently effecting a deceleration of the type as it approaches the platen to reduce the noise of impact and give strong leverage of the key-action upon the type to press the same firmly upon the platen; a line from the fulcrum of the forward link to the printing point nearly passing through the forward pivot of the type-carrier at the moment of printing, said forward link being substantially shorter and pivoted higher than said rear link and normally extending upwardly and rearwardly from its pivot, and the rear link normally extending toward the pivot of the forward link, the weight of the type-carrier lying mainly in line with its two pivots, and said type-car-

rier and said rear link being weighted near their articulations to each other to increase the shock of impact of the type against the platen, and render the linkage efficient to print at a decelerated speed of the striking type, the length of the type-carrier between its pivots being approximately equal to the length of the forward link and less than the length of the rear link, and key-controlled means to operate said rear link.

7. In a front-strike typewriting machine, the combination with a platen, of a system of type-keys, a system of rearwardly-extending key-levers whereon the keys are mounted, said key-levers in the form of bell-cranks which at their rear portions turn upwardly and are pivoted at their upper portions, a system of pivoted sub-levers which extend up and down and against which the upwardly-extending arms of the key-levers swing edge-wise, and a system of type-linkages to which the sub-levers are connected by means of links extending forwardly from the sub-levers to the type-linkages, the vertical arms of the key-levers being arranged to roll upon the sub-levers, each type-linkage including a rear drive-link connected to its sub-lever, and also including a forward upstanding guide-link, and also including a type-carrier pivoted upon said links and normally in folded cumbent position, the point of contact between the forward upstanding key-lever arm and the sub-lever being normally close to the key-lever pivot, and the contact between the key-lever and the sub-lever remaining near said pivot throughout a substantial portion of the key depression, and being again gradually shifted down to a point of nearest approach to the pivoted sub-lever, which point is reached when the type-linkage is substantially unfolded and the type-carrier begins its relatively slow rearward floating movement, the decrease of the leverage being reduced but little, if any, during the remainder of the floating stroke of the type-carrier, to avoid unnecessary speeding of the type at the conclusion of the printing stroke, the weight of the linkage tending to absorb the momentum of the operator's hand, the forward or guide link forming an obtuse angle with the type-carrier at the moment of printing.

8. In a front-strike typewriting machine, the combination with a platen and a system of normally folded front-strike type-linkages, each including a rear drive-link, a forward guide-link and a type-float, of a system of key-levers in the form of bell-cranks, and a system of upright sub-levers connected to said type-linkages and said key-levers, said bell-cranks having upstanding arms constructed to roll upon said upright sub-levers to effect reduction of the leverage of the keys throughout the printing strokes; said sub-levers being of the third order and pivoted at their lower ends below the key-lever elbows, and at their

upper ends having links extending forwardly to the type-linkages; the downward movement of each key effecting a rearward movement of its sub-lever, the latter standing edge to edge in line with the upstanding arm of the key-lever in rear thereof.

9. Machine constructed according to claim 8, the type-linkage system being mounted between the keys and the sub-lever system, and the system of type-floats lying between the system of sub-levers and the system of guide-links; said sub-levers arranged in converging planes and the upstanding arms of the key-levers being correspondingly arranged for rolling upon the sub-levers, said key-levers working in vertical planes, and the system of upstanding arms at their upper ends being of less width than the system of key-levers at their elbows.

10. In a typewriting machine, the combination with a platen and a system of type-linkages including links and type-carriers mounted thereon, of keys for operating said type-linkages, each of said linkages including a type-carrier pivoted upon the other members of the linkage, and springs to take up the play at articulations of the type-carrier to its supports in a manner to avoid knocking of said articulations as the result of the impact of the types against the platen.

11. In a typewriting machine, the combination with a platen and a system of type-linkages including links and type-carriers mounted thereon, of keys for operating said type-linkages, each of said linkages including a type-carrier pivoted upon the other members of the linkage, and springs to take up the play at articulations of the type-carrier to its supports in a manner to avoid knocking of said articulations as the result of the impact of the types against the platen, each spring connected to pull the type-carrier against its supporting link and also to pull said link against the pivot upon which it rocks.

12. In a typewriting machine, the combination with a platen and a system of type-linkages including links and type-carriers mounted thereon, of keys for operating said type-linkages, each of said linkages including a type-carrier pivoted upon the other members of the linkage, and springs to take up the play at articulations of the type-carrier to its supports in a manner to avoid knocking of said articulations as the result of the impact of the types against the platen, each system of type-linkages including a forward and rear link, and the type-carrier pivoted upon said links, and each spring being connected to the forward end of the type-carrier to pull the same down together with the forward link, the spring passing about through the axis of the pivot and extending substantially towards the pivot of the guide-link upon the framework of the machine.

13. In a typewriting machine, the combination with a platen and a system of key-driven type-linkages, each including a type-carrier and links upon which it is mounted, of springs opposing the tendency of linkage joints to knock by reason of the impacts of the types against the platen.

14. In a front-strike typewriting machine, the combination with a platen, of a system of type-linkages, each including a rear link and a front link pivoted upon the framework and a triangular type-carrier normally folded and pivoted on the free ends of said links for an upward unfolding motion and a rearward floating motion to the platen, each type-carrier having a type at its upper end and having its sides about equal in length, the type-carriers compactly occupying a position in rear of the forward links and with their rear type-ends directly overlying the pivots of the rear links, the length of the rear link being about equal to the rear side of the type-carrier, said rear link swinging through substantially less than ninety degrees to printing position and normally extending towards the lower pivot of the front link and about in line therewith, the traveling pivot 71 being normally spaced considerably back of the pivot 69, the forward link being substantially shorter than the rear link and also standing at a substantially higher elevation, so that in printing position the direction of the lower side of the type-carrier is obliquely downward and backward from the front link to the rear link, said front link in printing position extending obliquely upward and backward, and the rear link in printing position standing about upright, whereby the speed of the type itself when close to the platen is greatly decelerated, relatively to the remainder of the linkage, to minimize the noise of impact of the type on the platen, the type-carrier turning relatively towards the left about pivot 71 as the latter travels rearwardly, the type being given an independent movement of retardation about said traveling pivot 71.

15. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an upward unfolding motion and a rearward floating motion to the platen, said links being pivoted upon a system of individual radial plates or hangers, each inclusive of a plate, with forward and rear arms branching from said plate, the system of plates being fixed in a system of slots formed in a segment, said slots radiating downwardly and forwardly from the printing point, bolts rigidly holding the plates in the slots, each bolt having a head catching over adjoining hangers, a common segment or fastening plate sur-

mounting the plates and held down thereon by the heads of said bolts, said bolts extending through holes formed in the segment, said bolts being thinned or having flattened sides to clear the hanger-plates and to permit the endwise insertion or withdrawal of the plates while the loosened bolts remain in place, and nuts to draw said bolts tight upon the fastening plate, the latter engaging the edges of the hangers which protrude from the segment, each hanger-plate having a shouldered portion which fits upon the finished forward face of the segment, the hanger having a shoulder formed thereon above the inner or finished face of the segment, the rear branch of each type-hanger having a guiding horn for the drive-link.

16. Machine constructed according to claim 14, in which each forward guide-link is folded lengthwise and also given a U-shape for the purpose set forth, the upper end of the link formed of opposite ears to bestride a type-carrier pivot, said pivot having oppositely projecting central stud-portions extending through said opposite ears and headed thereover, a guiding nib extending upwardly from the forward hub-portion of the type-carrier, and a segmental general guide overlying said forward links, said guide radially slotted on its under side, said nibs working in said radial slots, and guiding and supporting the type-carrier in its movement towards the central fixed type-guide, each guide-link having at its bottom corresponding ears embracing the upper end of the hanger-arm and similarly pivoted thereto.

17. The combination with a platen, of a type-linkage below the platen and including a rear drive-link which is normally cumbent, a forwardly-extending link, and a type-carrier pivoted upon said links and normally folded down, whereby at the operation of said drive-link the linkage unfolds rapidly until the type-carrier is fully elevated and floats slowly rearwardly upon the links against the platen, an operating lever connected to said drive-link, and a key-lever, each of said levers extending from its fulcrum towards the fulcrum of the other lever, said key-lever having a rolling engagement with said operating lever, including an edge which has a flattened curve terminating at its ends in dwell-portions near the fulcrums of said levers, the first dwell-portion affording a great leverage to the key, to slow down the early portion of the unfolding movement of the type-linkage, and the other dwell-portion giving a much-reduced leverage of the key upon the linkage, to speed the linkage in its rearwardly-floating movement to strike the type against the platen.

18. In a standard front-strike typewriting machine modified substantially as set forth, the combination with a system of type-linkages and a system of key-bearing bell-cranks

to operate said linkages, upwardly extending arms operated by said bell-crank and having rear tappets thereon, of a universal bar in the form of a bail operated by said tappets, an arm connected to said universal 5 bar, a thrust-link extending upwardly from said arm, and a carriage-feeding dog-rocker having an arm engaged by the upper end of said thrust-link, said link being longitudinally slotted on its upper end to fit detachably upon an operating pin provided upon 10 said rocker-arm, said link having two portion, one of which is threaded within the other, to render the link extensible for correction of its length.

19. In a front-strike typewriting machine, the combination with a platen, of a system of type-keys, a system of key-levers having bodies extending rearwardly from the keys, 20 said key-levers in the form of elbows which at their rear portions form arms which turn upwardly and are pivoted at their upper portions, a system of pivoted sub-levers which extend up and down and against which the 25 upwardly-extending arms of the key-levers swing edgewise, and a system of type-linkages to which the sub-levers are connected by means of links extending forwardly from the upper ends of the sub-levers to the type- 30 linkages, the upwardly-extending arms of the key-levers being arranged to roll downwardly upon the sub-levers, each type-linkage including a rear drive-link connected to its sub-lever, and also including a forward upstanding 35 guide-link, and also including a type-carrier pivoted upon said links and normally in folded cumbent position, said sub-levers being of the third order and fulcrumed at their lower ends, and being in rear of the 40 key-levers, and said linkages being in rear of the keys and above the rearwardly-extending bodies of the key-levers and in front of the upwardly-extending arms of the key-levers.

20. In a front-strike typewriting machine, the combination with a platen, of a system of type-keys, a system of key-levers having bodies extending rearwardly from the keys, said key-levers in the form of elbows whose portions form arms which extend upwardly and are pivoted at their upper end-portions, a system of pivoted sub-levers which extend up and down and against which the upwardly-extending arms of the key-levers swing edgewise, and an arcuate system of radially arranged type-linkages to which the 45 sub-levers are connected, said key-levers working in substantially vertical planes, said rear key-lever-arms forming a transverse row and having up-and-down treads, said sub-levers being pivoted at their lower ends, said sub-levers being of varied lengths to accommodate the arcuate arrangement of the system of type-linkages, and said type-linkages being 50 below the front of the platen and above the key-lever bodies and forward of the upwardly-extending arms, returning springs being connected to said key-levers, and returning 55 springs being also connected to said type-linkages and radiating forwardly and downwardly from said drive-links from points near the fulcrums thereof.

23. In a front-strike typewriting machine, the combination with a platen, of a system of type-keys, a system of rearwardly-extending key-levers whereon the keys are mounted, said key-levers in the form of elbows which 60 at their rear portions turn upwardly and are 65

wardly-extending arms, the system of type-linkages being narrower than the system of key-levers, the width of the system of sub-levers at the top being about equal to the width of the system of type-linkages, said 70 system of sub-levers fanning out from side to side and at their lower ends about equal in width to the key-lever system, said key-levers having rocker-portions bent radially to correspond with the spreading arrangement of the sub-levers.

21. In a front-strike typewriting machine, the combination with a platen, of a system of type-keys, a system of key-levers, a system of pivoted sub-levers, a system of type-linkages 80 to which the sub-levers are connected, each type-linkage including a rear drive-link connected to its sub-lever, and also including a forward upstanding guide-link, and also including a type-carrier pivoted upon said links and normally in folded cumbent position, a means for guiding the drive-links between their ends, a slotted radial guide for the type-linkages, each type-carrier laterally guided thereby at the region of its articulation to its guide-link, the radial guide overlying the system of guide-links, the links and type-carriers being constantly guided throughout their printing strokes, and a center guide at the printing point common to 85 all of the type-carriers.

22. In a front-strike typewriting machine, the combination with a platen, of a system of type-keys, a system of key-levers having bodies extending rearwardly from the keys, 100 said key-levers in the form of elbows whose portions form arms which extend upwardly and are pivoted at their upper end-portions, a system of pivoted sub-levers which extend up and down and against which the upwardly-extending arms of the key-levers swing edgewise, and an arcuate system of radially arranged type-linkages to which the sub-levers are connected, said key-levers working 105 in substantially vertical planes, said rear key-lever-arms forming a transverse row and having up-and-down treads, said sub-levers being pivoted at their lower ends, said sub-levers being of varied lengths to accommodate the arcuate arrangement of the system of type-linkages, and said type-linkages being 110 below the front of the platen and above the key-lever bodies and forward of the upwardly-extending arms, returning springs being connected to said key-levers, and returning springs being also connected to said type-linkages and radiating forwardly and downwardly from said drive-links from points 115 near the fulcrums thereof.

23. In a front-strike typewriting machine, the combination with a platen, of a system of type-keys, a system of rearwardly-extending key-levers whereon the keys are mounted, said key-levers in the form of elbows which 120 at their rear portions turn upwardly and are 125

pivoted at their upper portions, a system of pivoted sub-levers which extend up and down and against which the upwardly-extending arms of the key-levers swing edgewise, and 5 an arcuate system of type-linkages to which the sub-levers are connected by means of links extending forwardly from the sub-levers to the type-linkages, said key-levers working in substantially vertical planes and pivoted about the level of the keys, said rear key-lever-arms having up-and-down treads, said 10 sub-levers being pivoted at their lower ends, said sub-levers having means to guide their upper and lower ends and being of varied 15 lengths to accommodate the arcuate arrangement of the system of type-linkages, said sub-levers extending upwardly in rear of and above the row of key-lever-arms and being pivotally connected to the type-linkages at 20 points above the key-levers, said upright arms of the key-levers forming treads of rocker-portions to roll down upon the sub-levers, the sub-levers at their upper ends standing about directly in rear of and level with the points 25 of engagement of the pull-links with the drive-links.

24. In combination, a system of rearwardly-striking type-linkages, a system of keys, a system of connections from the keys to the 30 type-linkages constructed to afford a maximum leverage of the keys upon the type-linkages at the beginning of the key-strokes and decreasing leverage throughout the printing strokes, each type-linkage including a cum- 35 bent rear link, an upstanding front link, both links pivoted upon the framework, and a carrier normally folded and pivoted upon the free ends of said links for an upward unfolding motion and a rearward floating motion 40 to the platen, said type-carrier having a type at its upper end, the upper pivot of the forward link being at a point substantially higher than the pivot of the free end of the rear link and moving in a rearward and downward path at the conclusion 45 of the printing stroke, thereby rotating reversely the type-carrier upon its point of pivoting to the rear link and effective to decelerate the type as it approaches closely to the platen to reduce the noise of 50 impact and give strong leverage of the key-action upon the type to press the same firmly upon the platen, said upstanding link being fulcrumed at a point substantially higher than the fulcrum of the rear link, and the 55 free end of the rear link being normally nearly in line with the fulcrums of both links.

25. In combination, a system of rearwardly-striking type-linkages, a system of keys, a system of connections from the keys to the 60 type-linkages affording a maximum leverage of the keys upon the type-linkages at the beginning of the key-strokes and enormously decreasing leverage during the printing strokes, each type-linkage including a rear 65 drive-link, a front guide-link pivoted upon

the framework, and a carrier normally folded and pivoted upon the free ends of said links for an upward unfolding motion followed by a rearward floating motion to the platen, said type-carrier having a type at its upper end, the free pivot of the guide-link being at a point substantially higher than the free pivot of the drive-link and moving in a rearward and downward path at the conclusion of the printing stroke, and effective to rotate reversely the type-carrier upon its point of pivoting to the drive-link and decelerate the type as it approaches the platen, a line from the fulcrum of the forward link to the printing point passing immediately in rear of the forward pivot of the type-carrier at the moment of printing, said forward link being substantially shorter and pivoted higher than said rear link and normally extending upwardly and rearwardly from its pivot, and the rear link normally extending toward the pivot of the forward link.

26. Machine constructed in accordance with claim 25, in which the weight of the type-carrier lies mainly in line with its two pivots, said type-carrier and said rear link being weighted near their articulations to each other to increase the shock of impact of the type against the platen, and render the linkage efficient to print at a decelerated speed of the striking type.

27. In a front-strike typewriting machine, the combination with a platen, of a system of type-keys, a system of rearwardly-extending key-levers whereon the keys are mounted, said key-levers in the form of elbows which at their rear portions turn upwardly and are pivoted at their upper portions, a system of pivoted sub-levers which extend up and down and against which the upwardly-extending arms of the key-levers swing rearwardly edgewise, and a system of type-linkages to which the sub-levers are connected, the vertical arms of the key-levers being arranged to roll upon flattened curves provided upon the sub-levers, each type-linkage including a rear drive-link connected to its sub-lever, and also including a forward upstanding guide-link, and also including a type-carrier pivoted upon said links and normally in folded cumbent position, a dwell being provided at the point of contact between the forward upstanding key-lever arm and the sub-lever, said dwell being close to the key-lever-pivot, and the contact between the key-lever and the sub-lever remaining upon said dwell and near said pivot throughout a substantial portion of the key depression, the flattened curve shifting the point of contact rapidly to a lower dwell provided at the point of nearest approach to the pivoted sub-lever, which lower dwell is reached when the type-linkage is substantially unfolded and the type-carrier begins its relatively slow rearward floating movement, the decrease of the

- leverage being reduced but little upon the lower dwell during the remainder of the floating stroke of the type-carrier, to avoid overspeeding the type at the conclusion of the 5 printing stroke, the forward or guide-link forming a slightly obtuse angle with the type-carrier at the moment of printing, with the type-carrier-pivot forward of a line joining the guide-link fulcrum to the printing point.
- 10 28. In a front-strike typewriting machine, the combination with a platen and a system of normally folded front-strike type-linkages, each including a rear drive-link, a forward guide-link and a type-float, of a system 15 of key-levers in the form of elbows, and a system of upright sub-levers connected to said type-linkages and said key-levers, said key-levers having upstanding arms constructed to roll upon said upright sub-levers to effect reduction of the leverage of the keys 20 throughout the printing strokes, said sub-levers being of the third order and pivoted at their lower ends below the key-lever-elbows, and at their upper ends having links extending forwardly to the type-linkages.
- 25 29. In a front-strike typewriting machine, the combination with a platen, of a system of type-linkages, each including a rear link and a front link pivoted upon the framework and a triangular type-carrier normally folded and pivoted on the free ends of said links for an 30 upward unfolding motion and a rearward floating motion to the platen, each type-carrier having a type at its upper end and having its sides about equal in length, the type-carriers compactly occupying a position in rear of the forward links and with their rear type-ends directly overlying the pivots of the rear links, the length of the rear link being about equal to the rear side of the type-carrier, 35 said rear link normally extending towards the lower pivot of the front link, said front link in printing position extending obliquely upward and backward, and the rear link in printing position, standing about upright, whereby the speed of the type itself when close to the platen is greatly decelerated, relatively to the remainder of the linkage, to minimize the noise of impact of the type on 40 the platen, the type-carrier turning relatively towards the left about pivot 71 as the latter travels rearwardly.
- 45 30. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 50 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and means detachably fastening the plates in the slots.
- 55 31. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 60 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and means detachably fastening the plates in the slots.
- 65 32. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 70 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and means detachably fastening the plates in the slots.
- 75 33. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 80 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and bolts rigidly holding the plates in the slots, each bolt having a head catching over adjacent hangers.
- 85 34. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 90 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and bolts rigidly holding the plates in the slots, each bolt having a head catching over adjacent hangers.
- 95 35. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 100 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and bolts rigidly holding the plates in the slots, each bolt having a head catching over adjacent hangers.
- 105 36. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 110 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and bolts rigidly holding the plates in the slots, each bolt having a head catching over adjacent hangers, and a common segment or fastening plate surmounting the plates and held down thereon by the 115 heads of said bolts.
- 120 37. In combination, a system of rearwardly-striking type-linkages, a system of keys, a system of connections from the keys to the type-linkages, each type-linkage including a rear drive-link, a front guide-link, and a type-carrier normally folded down and pivoted upon the free ends of said links for an 125 upward unfolding motion and a rearward floating motion to the platen, said links being pivoted upon a system of individual radial hangers, each inclusive of a plate, with forward and rear link-carrying arms branching from said plate, a segment having slots in which the system of plates is fixed, said slots radiating downwardly and forwardly from the printing point, and bolts rigidly holding the plates in the slots, each bolt having a head catching over adjacent hangers, and a common segment or fastening plate surmounting the plates and held down thereon by the 130 heads of said bolts.

ing pivoted upon a system of individual radial hangers, each inclusive of a plate, with forward and rear link-carrying arms branching from said plate, a segment having slots 5 in which the system of plates is fixed, said slots radiating downwardly and forwardly from the printing point, bolts rigidly holding the plates in the slots, each bolt having a head catching over adjacent hangers, said 10 bolts extending through holes formed in the segment, said bolts being thinned or having flattened sides to clear the hanger-plates and to permit the endwise insertion or withdrawal of the plates while the loosened bolts remain 15 in place, and nuts to draw said bolts tight upon the fastening plate.

35. In combination, a system of rearwardly-striking type-linkages, a system of keys, a system of connections from the keys to the 20 type-linkages, each type-linkage including a rear drive-link, a front guide-link, and a type-carrier normally folded down and pivoted upon the free ends of said links for an upward unfolding motion and a rearward 25 floating motion to the platen, said links, being pivoted upon a system of individual radial hangers, each inclusive of a plate, with forward and rear link-carrying arms branching from said plate, a segment having slots 30 in which the system of plates is fixed, said slots radiating downwardly and forwardly from the printing point, and bolts rigidly holding the plates in the slots, each bolt having a head catching over adjacent hangers, 35 said bolts extending through holes formed in the segment, the fastening plate engaging the edges of the hangers which protrude from the segment, each hanger having a shouldered portion which fits upon the finished 40 forward face of the segment, the hanger having a shoulder formed thereon above the inner or finished face of the segment.

36. In combination, a system of rearwardly-striking type-linkages, a system of keys, 45 a system of connections from the keys to the type-linkages, each type-linkage including a rear drive-link, a front guide-link, and a type-carrier normally folded down and pivoted upon the free ends of said links for an 50 upward unfolding motion and a rearward floating motion to the platen, said links being pivoted upon a system of individual radial hangers, each inclusive of a plate, with forward and rear link-carrying arms branching 55 from said plate, a segment having slots in which the system of plates is fixed, said slots radiating downwardly and forwardly from the printing point, and means detachably fastening the plates in the slots, the rear 60 branch of each hanger having a guiding horn for the drive-link.

37. Machine constructed according to claim 29, in which each forward guide-link is folded lengthwise and also gives a U-shape for the 65 purpose set forth, the upper end of the link

formed of opposite ears to bestride a type-carrier-pivot, said pivot having oppositely projecting central stud-portions extending through said opposite ears and headed thereover, a guiding nib, and a segmental general 70 guide overlying said forward links, said guide radially slotted on its under side, said nibs working in said radial slots, and guiding and supporting the type-carrier in its movement towards the central fixed type-guide.
